UNITED STATES PATENT OFFICE.

PAUL GAUTIER, OF PARIS, FRANCE.

KINETOGRAPHIC CAMERA.

SPECIFICATION forming part of Letters Patent No. 595,620, dated December 14, 1897.

Application filed March 3, 1897. Serial No. 625,811. (No model.) Patented in Belgium January 11, 1896; No. 125,671; in France September 11, 1896, No. 259,599, and in England January 4, 1897, No. 212.

To all whom it may concern:

Be it known that I, PAUL GAUTIER, of Paris, France, have invented certain new and useful Improvements in Intermittently-Moving Apparatus for Taking or Displaying Photographs, (patented to me in France September 11, 1896, No. 259,599; in Belgium January 11, 1896, No. 125,671, and in England January 4, 1897, No. 212,) of which the following is a specification.

This invention relates to intermittently moving apparatus for taking or displaying photographs of moving objects, as will be described, referring to the accompanying drawings.

Figure 1 is a front view, and Fig. 2 a side view, of the moving parts of apparatus according to this invention. Fig. 3 is a view of detail.

20 The invention consists of an intermittently moving apparatus for taking or displaying photographs in which the film is drawn along a guide-passage by a cylinder operated by a clockwork mechanism.

25 Between two side plates 1 and 2 suitable clockwork is arranged to give intermittent rotary movement to a cylinder A, furnished with pins a, which pierce the film, drawing it along a guide-passage S and between the cylinder and the movable segment F to the guide-passage S'. The clockwork drives the spindle P, having on it a disk B, with crank-pin N, which is connected by link C to a lever D, pivoted on the axis of A and carrying a pawl

30 H, which engages a ratchet-wheel 3, fixed on the axis of A, thus advancing the cylinder step by step, while the pawl I prevents it from moving backward. A third pawl G engages another oppositely-toothed ratchet-wheel 4, also fixed on the axis of A. The lever D has

35 a projection M, which at a certain part of its stroke pushes an arm L, fixed to the pawl G, thus disengaging G from the ratchet-wheel 4.

As the spindle P revolves the link C reciprocates. As it ascends the pawl H moves 45 over one tooth of the ratchet-wheel 3 and engages with the next, the projection M at this time acting on L and disengaging the pawl G from the ratchet-wheel 4, and then as C descends the cylinder A is turned one tooth. 50 While C ascends again the cylinder A is held stationary by both pawls G and I, and the action is continuously repeated. Thus the film is held stationary during the ascent of the rod C and moves only during its descent. 55

Having now particularly described and ascertained the nature of my said invention and in what manner the same is to be performed, I declare that what I claim is—

1. In intermittently-moving apparatus for taking or displaying photographs, the combination of clockwork driving a crank having a link connected to a pawl-lever engaging a ratchet-wheel on the axis of a pinned cylinder moving the film, the pawl-lever being arranged to disengage, as the link ascends, a second lever having a pawl which engages an oppositely-toothed wheel on the axis of the cylinder and operating as the link descends to move the cylinder one tooth to a position 70 in which during the ascent of the link it is held by the second pawl and by a third pawl preventing back movement, substantially as described.

2. In combination the feeding-passages S 75 and S', the cylinder A adapted to engage the film to draw it through the passage, a disk B, means for rotating the same, and an operating connection between the disk and cylinder A, substantially as described. 80

In witness whereof I have hereunto set my hand in presence of two witnesses.

PAUL GAUTIER.

Witnesses:

EDWARD P. MACLEAN,
JULES TAYOLUT.
